UNITED STATES PATENT OFFICE.

WILLIAM PEARSALL, OF WORCESTER, MASSACHUSETTS, ASSIGNOR TO
MATTHEW J. WHITTAILE, OF WORCESTER, MASSACHUSETTS.

TUFTING MECHANISM FOR LOOMS.

No. 853,471.

Specification of Letters Patent.

Patented May 14, 1907.

Application filed February 23, 1904. Serial No. 194,707.

To all whom it may concern:

Be it known that I, WILLIAM PEARSALL, a subject of the King of England, residing at Worcester, in the county of Worcester and 5 State of Massachusetts, have invented a new and useful Tufting Mechanism for Looms, of which the following is a specification.

This invention relates to a tufting mechanism for inserting the yarns or threads which 10 form the tufts or piles which constitute the wearing surface of a fabric.

The especial object of this invention is to provide a strong, simple, and efficient tufting mechanism which can be operated at 15 high speed to produce a high grade of fabric.

To these ends, this invention consists of the parts and combinations of parts as hereinafter described and more particularly pointed out in the claims at the end of this 20 specification.

In the accompanying five sheets of drawings, Figure 1 is a front view of sufficient parts of a loom to partly illustrate the application of this invention thereto. Fig. 2 is a 25 partial transverse sectional view illustrating the connections which carry the cutting knives. Fig. 3 is a transverse sectional view of the loom. Fig. 4 is an enlarged fragmentary sectional view of one of the vertically 30 movable slides or rack-bars which carry the ends of the worsted or threads. Fig. 5 is a fragmentary front view thereof. Fig. 6 is a fragmentary view of the cutting knife and the track or way upon which the same slides.

35 Figs. 7 to 13 inclusive are diagrammatic views illustrating the operation of the nippers in inserting a line of tufts across the fabric. Fig. 14 is a detail view of the connections for opening and closing the nippers.

40 Figs. 15 to 18 are detail views illustrating the operation of the pile supporting bail or wire; and Fig. 19 is a detail view of the cams and connections operating the retaining wire.

In a loom constructed according to this invention as herein illustrated, the yarns or threads which are to form the tufts or piles constituting the wearing surface of a fabric may be drawn from the ordinary creels or frames, the ends of these yarns being mounted 45 in a rack which comprises a series of vertically movable slides or rack-bars. The slides or rack-bars are shifted or moved up and down by selecting devices to bring the

properly colored threads in position to form one of the lines of tufts or piles of the fabric. 55 Any desired selecting devices may be used for shifting the vertically movable slides. Co-operating with the rack are nippers or swinging-jaws which engage the projecting ends of the yarns when the same are brought 60 to proper position. The nippers, after they have grasped the yarn ends, are moved back far enough to draw out the length of yarn required for a tuft or pile of the fabric. The 65 yarn is then cut off by the transverse passage of a cutting knife. The nippers then continue their travel and swing downwardly to carry their yarn down into the chain which forms the foundation or backing of the fabric. While the yarn is thus held down into place 70 by the nippers, weft threads are inserted in the shed in the weft-threads. The nippers are then released, and the weft threads are beaten up by the lay. The reed of the lay is formed by a number of thin plates or blades 75 which enter the slots of a comb or metal plate. This comb is provided with an inclined forward edge and with a barb-shaped projection or detent, and as the weft threads snap down behind this detent, the detent 80 will form a shoulder which will raise the free ends of the tufts or piles. The nippers then swing back and also tend to comb up or straighten the piles. To prevent the overhanging edges of the pile from being drawn 85 down at the next operation of the nippers, I also provide a retaining bail or wire which engages behind the successively formed piles and which is intermittently raised and swung 90 back and forth to engage the piles as formed.

Referring to the accompanying drawings for a detail description of an apparatus embodying this invention, as shown most clearly in Fig. 3, T designates the yarns or threads which are drawn from any suitable 95 source of supply, and are clamped near their ends in a rack comprising a number of independent, vertically movable slides or rack-bars B which together constitute the rack for presenting the threads in proper position to be engaged by a series of nippers N. The rack-bars B are operated by threads L from any suitable selecting mechanism, and are held in adjusted position by a catch-bar 15, which, when released, permits all the slides 100 or rack-bars B to return to lowest position.

The nippers which co-operate with the rack-bars B, as shown, are mounted to swing or turn with a rock-shaft 16. Secured on the rock-shaft 16 are side-frames 17 which are connected by a cross-bar 18 and by an operating rock-shaft 21. Extending up from the cross-bar 18 are the stationary pieces 19 of the nippers, and pivoted to each stationary piece 19 is a movable jaw 20 having a tail-piece which extends down between guide-pins p shown in Fig. 3 and is connected at its lower end to a spring 22 for normally holding the nippers closed. The springs 22 are connected to a substantially vertical plate or arm extending down from the operating rock-shaft 21. The operating rock-shaft 21 is also provided with an inclined plate or arm which acts as a cam-plate to open the movable jaws 20.

20 So long as the rock-shaft 21 is locked or held from turning by the catch mechanism illustrated in Fig. 14, the movable jaws 20 will be held closed by the tension of the springs 22. So soon as the catches are released, the tension of the springs 22 act to turn the rock-shaft 21, causing the movable jaws 20 to fly open.

Each of the rack-bars B comprise side-plates 10 connected by cross-pieces 11. 30 Mounted on each of the cross-pieces 11 is a spring 12 for holding one of the threads in place, while permitting the end of the thread to be advanced when required.

When the nippers have drawn forward the required lengths of thread or yarn, the yarns are cut off by a knife K which is fastened in place by a spring S upon the carriage 23. The carriage 23 is mounted to be moved back and forth upon a guideway 24 by a rope R, 40 and also carried by the guideway 24 is a comb or cutting plate, P which co-operates with the knife K.

The connections for moving the knife K into and out of operative position are most clearly illustrated in Figs. 1 and 2. As shown in these figures, the guideway 24 is provided at its ends with projections 25 which are supported by inclined cams 26. Extending back from the guideway 24, as 50 shown in Fig. 2, are links 27 which are connected to arms 28 extending down from slides 29. Each of the slides 29 is mounted on rollers 30 and is moved in one direction by a spring 31, and in the opposite direction by a gear 32 which may be mounted on a cam-actuated rock-shaft and which meshes with a rack carried by the slide 29. The ways 26 at the opposite sides of the loom frame which support the projections 25 are of such inclination that as the knife K is drawn into proper operative position the cutting plate or comb P will be carried down with an inclined or diagonal movement, more easily forcing its way between the worsteds, where-

by it is accurately brought to position to sever the yarns which are desired for the particular tuft or pile being formed.

The body part or chain of the fabric may be woven by any of the ordinary loom constructions. For example, as shown in Fig. 3, 70 the warp threads may be operated by heddles mounted in the heddle-frames H, while the weft threads may be inserted in place in any ordinary way. In practice, I have used a special needle loom construction which 75 forms the subject matter of a separate application for patent, which I have executed on even date herewith, filed in the United States Patent Office Feb. 23, 1904, Serial No. 194,708.

80 The completed fabric passes over the comb C having a slotted forward edge, and having a rearwardly inclined bar or projection. The shape of this comb is of particular importance in a mechanism constructed according 85 to this invention, because as the weft threads are successively beaten up over the bar or projection of this comb, this projection or bar will serve to raise or lift the free end of the pile up to proper position. The weft 90 threads are beaten up by the lay E having a reed formed by narrow plates or sheet metal pieces 34. Also co-operating with the comb C, I provide a pile supporting bail or wire W, which is intermittently raised and moved 95 back and then forward to hold up the successively formed lines of piles.

The sequence of operation of the nippers in carrying a pile into proper position, is most clearly illustrated in Figs. 7 to 13 inclusive. 100 As shown in Fig. 7, the nippers N are shown as just engaging the properly colored yarns which have been brought up to selected position. The nippers then draw out the required length of yarn, as shown in Fig. 8, and the knife K is moved back and downwardly to operative position to sever or cut off the selected yarns. The knife K is then again raised leaving the required lengths of yarn in the grippers, as shown in Figs. 3 and 9. The 105 grippers then continue their motion and carry the tuft or length of yarn required down onto the comb C, as illustrated in Fig. 10. One or more weft threads f are then laid in position, for example, by a needle M as shown in Fig. 11. The nippers N are then released and the fabric is beaten up so that as the weft threads f are carried up over the projection 33 of the comb, this projection will serve to raise the pile so that it will stand up from the 120 face of the fabric. As the nippers are returned to position as shown in Fig. 13, they will also serve to insure the proper raising of the pile.

The operating connections for opening and closing the nippers at proper times are most clearly illustrated in Fig. 14. As shown in this figure, an operating arm 34 is secured on

the rock-shaft 21, and connected with the operating arm 34 is a locking latch 35 which will engage a tooth or stop 36 on the rock-shaft 16. Co-operating with the arm 34 is a rocker 46 which is moved in one direction by a spring 37, and in the opposite direction by a link 38 pivotally connected to a cam operated lever 39. Also extending from the lever 39 is a releasing pin or link 40. By means of this construction, when the nippers N, extend up to the position shown in Fig. 14, the rocker 46 by engagement with the arm 34 will close said nippers N and the catch 35 will hold said nippers in their closed position. When the nippers N are in inverted position, the latch 35 will be brought into position to be engaged by the releasing pin 40, which will release said latch 35 and permit the nippers N to fly open as illustrated in Fig. 12.

20 The operation of the pile supporting bail or wire W is most clearly illustrated in Figs. 15 to 19. As shown in Fig. 15, the bail W will engage behind a freshly formed pile, and as shown in Fig. 16, it will hold said pile out of the way while a fresh tuft is brought into position. After a tuft is beaten up as shown in Fig. 17, the bail or retaining wire W is lifted and swung back as shown by dotted lines.

30 The connections for imparting the proper motions to the bail or retaining wire W are most clearly illustrated in Fig. 19. As shown in this figure, the retaining bail or wire W is mounted in arms 41. Extending down from the arms 41 are links 42 which are connected to links 43 which are operated by a cam 44. At their ends the arms 41 are connected to bell-crank levers 45 which are connected by links 46 to arms 47 operated by a cam 48. The cam 44 serves to lift the retaining wire or loop W to the position indicated by dotted lines in Fig. 17, while the cam 48 gives the retaining wire its forward and backward motion.

45 I am aware that numerous changes may be made in the construction of tufting mechanisms for looms without departing from the scope of this invention as expressed in the claims. I do not wish, therefore, to be limited to the construction I have herein shown and described, but

What I do claim and desire to secure by Letters Patent of the United States is:—

1. In a tufting mechanism for looms, the combination of a rack adapted to hold the ends of yarns projecting therefrom, and means for severing the projecting ends of the yarn, comprising a guide-plate having comb-teeth on the lower edge thereof, means for moving the guide plate downwardly in an inclined direction toward the face of the rack, a knife mounted on the guide-frame, and means for moving the guide laterally along the guide-frame. 55

2. In a tufting mechanism for looms, the combination of a rack having the ends of yarns projecting therefrom, means for severing the projecting ends of the yarn consisting of a guide plate with comb-teeth on the lower edge thereof, said guide plate being mounted 60 so that the same can be moved down and toward the face of the rack, with a knife mounted on the guide frame, and movable thereon, a cord for moving said knife, and means for inserting the cut off pieces of yarn to 70 form the pile of a fabric. 75

3. In a tufting loom, the combination of a breast beam or support for completed fabric having comb-teeth or slots at its rear edge for receiving the reed blades, and having an 80 inclined rear edge and bar serving to raise the pile when the fabric is beaten up, a retaining wire, and means for operating the same to engage behind successively formed tufts. 85

4. In a tufting loom, the combination of a breast-beam or support for completed fabric having comb-teeth or slots at its rear edge receiving the reed-blades of the lay, and having an inclined rear edge and bar which serve to raise the piles, a retaining wire, with 90 two cams connected to operate the retaining wire to engage behind successively formed tufts, and move the same forward out of the way.

In testimony whereof I have hereunto set 95 my hand, in the presence of two subscribing witnesses.

WILLIAM PEARSALL.
